UNITED STATES PATENT OFFICE.

SIMON LAKE, OF MILFORD, CONNECTICUT.

APPARATUS FOR MAKING METAL CASTINGS.

1,272,062.

Specification of Letters Patent. Patented July 9, 1918.

Application filed August 9, 1917. Serial No. 185,277.

To all whom it may concern:

Be it known that I, SIMON LAKE, a citizen of the United States, residing at Milford, in the county of New Haven and State 5 of Connecticut, have invented certain new and useful Improvements in Apparatus for Making Metal Castings, of which the following is a specification.

The invention has for its object to provide 10 an apparatus which will permit the molten metal to flow freely into the mold without trapping air, thereby providing a solid or dense casting in which blow holes and surface indentations or imperfections are positively avoided, hence minimizing the cost of 15 machining and planing, and the consequent cost in the production of the finished article, the construction and operation being such that a partial vacuum is created within the 20 mold to permit the free flow of the molten metal as it is poured into the mold. Another object of the invention is to provide means for "stamping" the metal so as to positively exclude all air pockets, said stamping means 25 also serving as a valve for controlling the admission of the metal to the mold. Another object of the invention is to provide means for permitting the escape of excess 30 quantities of air and gases which may accumulate in the mold either during the process of pouring the metal, or through dampness of the molding sand.

The invention consists in constructing a mold of two sections, commonly known as 35 the cope and drag, said sections being connected air-tight and mounted upon a base, and covered by a top plate, the said top plate being also connected air-tight to the cope and having a hopper mounted thereon into 40 which the molten metal is poured and allowed to set sufficiently to permit air bubbles to escape therefrom, said hopper having a plunger valve controlling the admission of the molten metal to the mold, and said plate 45 also having an exhaust pipe connected thereto and adapted for connection with a suction pump whereby to withdraw air from the mold so as to create a partial vacuum therein, and said plate also having a vent nor- 50 mally closed by a diaphragm of considerably less strength than the framing of the cope and drag so as to permit the escape of air and gas without injury to the framing of the apparatus. The invention further con- 55 sists in certain novel features of construction, combinations and arrangements of parts

as will be hereinafter described and then claimed.

In the drawings, illustrating the invention, in the several figures of which like parts are similarly designated, Figure 1 is a side elevation of my improved mold. Fig. 2 is a vertical transverse sectional view of the same, parts being broken away. Fig. 3 is a partial vertical section of a modified 65 form of the lower section.

The mold proper is preferably constructed of two sections or flasks, viz., a lower section or flask 1, providing a frame for holding the drag 2, and an upper section or flask 3 for holding the cope 4, the sections or flasks 1 and 3 being flanged at their upper and lower ends, as at 5, the abutting flanges of the said sections being securely fastened together as by bolts and nuts 6, as shown. The abutting 70 faces of the said flanges are provided with registering grooves 7 adapted for receiving a suitable plastic quick hardening material, such as plaster of Paris, putty, or a mixture of litharge and sand, so as to provide a seal 75 between the joint formed between the said flanges. Channels 8 are formed in the flanges 5 of the upper section and have their outer ends provided with threaded sockets 9 into which are screwed nipples of a pump or 80 pumps 10 by which the sealing material may be forced into the grooves 7.

The lower end of the section or flask 1 is closed preferably by a base plate 11, which is bolted to the lower flange 5 of the section 85 or flask 1, and the lower face of the said flange and the upper face of the said base plate 11 are provided with registering recesses to provide annular grooves or recesses 12 to which are connected pumps 13 90 for forcing a sealing material into the said grooves 12 in a similar manner to that described with respect to the grooves 7. While I show the base plate as a separate and detachable element of the lower section, it will, 95 of course, be understood that it may be formed integral with said section as shown in Fig. 3, thus avoiding the necessity of providing a sealed joint between the lower end of the lower section and its base. As 100 shown in Fig. 3, 1⁺ is the lower section and 11⁺ is its integral base. The grooves 7 and 12 are provided with vents 14 located, preferably, at a point diametrically opposite the pumps 10 and 13, respectively, whereby to 105 facilitate the complete filling, and consequent hermetic sealing of the joint.

The upper end of the section or flask 3 is closed by a plate 15, bolted to the upper flange 5 of the section or flask 3 and having its lower surface provided with an annular 5 recess designed to register with a similarly shaped recess formed in the upper face of the upper flange 5, providing an annular recess 16 adapted to receive a suitable packing material to form an air-tight joint between 10 the plate or cover 15 and the section or flask 3.

As stated, the flask 1 is designed to receive the drag 2 of the mold, and the upper section or flask 3 is designed to receive and hold the cope 4, and it might be stated here, 15 that, in practice, both the drag and the cope are constructed of any suitable material, such as sand or cement, or a composition of suitable material. The drag is also 20 formed with a core conforming to the shape of the article to be molded, and, in practice, the core is covered with molding sand, as indicated at 17, in Fig. 2 of the drawings. 18 designates the mold formed by the baked 25 materials of the drag and cope.

The mold 18 is formed with a feeding passage or channel 19 leading into its base or lower end, and with an outlet 20 extending from the extreme upper end of the mold, 30 said outlet being in communication with an exhaust passage extending from a vacuum pump (not shown), as will be hereinafter referred to, whereby as the molten metal is poured into the mold, the metal will be 35 permitted to flow freely into every crevice or compartment of the mold as will be best understood from the subsequent general description of the operation of the apparatus.

The top plate 15 is formed with a boss 40 21 upon which is securely bolted a casing 22 having a bore 23 registering with a bore 24 formed in the plate 15. Bolted upon the upper flanged end of the casing 22 is a hopper 25 into which the molten metal is 45 poured prior to its delivery to the mold. The walls of the hopper 25 are lined with a suitable refractory material 26, the said material being extended down into the bore 23 and into the opening 24, and of substantially 50 cylindrical form to provide a cylindrical passage 31 to receive the lower end of a plunger 27, which latter serves as a valve to control the flow of the molten metal into the passageway 19 leading to the mold proper. The plunger is preferably 55 constructed of a metallic core upon which is baked fire-clay, porcelain, or other suitable refractory material 30, and the said metal core or rod is provided throughout its 60 length with a plurality of concentric grooves or ribs 29 to provide a locking means so as to prevent the displacement of the refractory material 30. The lower end of the hopper 25 and the refractory lining 26, as 65 before stated, terminate in a cylindrical bore

31, and the inner face of the cylindrical bore of the refractory material 26, adjacent to the lower end of the cylindrical portion thereof, is provided with an annular recess 31', which communicates with a bore or passage 32 70 formed in the lining 26 and having its outer end in open communication with a bore 33 in a lug 33' integral with the casting 22, said bore 33 having its outer end threaded to receive the shank of a suitable pump 34 75 whereby to force suitable packing materials into the recess 31' so as to provide a sealed joint between the periphery of the plunger 27 and the cylindrical portion of the lining 26.

The plate 15 is formed, preferably diametrically opposite the boss 21, with a boss 39 having a transverse groove 40 in its upper face, which, with a plate 41 bolted upon the upper surface thereof provides a channelway for the reception of a gate-valve 42, the purpose of which will be explained hereinafter. Screwed into the plate 41 is an exhaust pipe 43, preferably lined with a refractory porous material, as shown at 44, 80 in Fig. 2. The pipe 43 is extended from a suitable suction pump (not shown), and is provided with a valve 45, whereby passage through the said pipe 43 may be controlled.

Arranged centrally of the plate 15 is a vent 46, the outer end of which is closed by a diaphragm 47 of comparatively lightweight material, which is designed to form a relief valve to permit the escape of excess pressures of gases, air, or steam within the mold which might accrue in the molding of the castings, and which oftentimes occur owing to dampness in the molding sand, and in the formation of gases during the melting and pouring of the metal into the mold. The hopper 25 is formed with a spout 48, and with a channel 49 leading into the hopper 25, whereby the hopper may be drained of materials after the mold has been filled, and, of course, before the metals have thoroughly cooled. The channel 49 is held normally closed by a plug 50, as shown in Fig. 2.

Associated with the hopper 25 is a ladle 51, shown in dotted lines in Fig. 1 of the drawings, which may extend from or be associated with suitable smelting furnaces, and which serves as a conveyer to supply the hopper with the material to be fed into the mold, and which may also serve as a chute to guide the molten metal into the mold as it is delivered from the smelting furnace.

The advantages of my improved apparatus may be best understood from the following description of the operation of the device:

After the mold is baked, and while still warm, the pouring receptacle or hopper 25 and the vent pipe 43 are secured to the upper

plate 15 and the plate valve 42 is inserted in the slot 40 and sealed so as to provide an air-tight joint, the inner end of the slot being preferably closed tight by a suitable sealing material, such as putty, litharge and sand, or other suitable material so that the air within the mold may be withdrawn through the said pipe 43. Metal is now poured into the hopper, and when bubbling ceases the plunger 27 is elevated sufficiently to permit the liquid metal to flow through the opening 19 into the mold, enough metal being poured into the mold to allow it to rise into the lower end of the vent tube a distance proportionate to the vacuum maintained and the specific gravity of the metal being poured. As soon as the mold is filled the valve plate 42 is driven in through the slot, thus shutting off further rise of metal in the vent pipe 43. The plunger 27 is then forced down upon the plastic metal to compress it in the mold, hence making the metal more compact and homogeneous.

When a number of castings are to be made from the same pattern, instead of using all sand surrounding the pattern in the flasks, I purpose making a semi-permanent mixture of cement or plaster, leaving only a small quantity of sand to be dried in the oven each time a casting is made; it being understood that no moisture should be in the sand surrounding the casting, otherwise steam might be generated and burst the mold. However, in order to avoid injury to the mold in such an event, I provide the vent 46, which is covered by the plate 47, as previously described. It will be seen that the plate 47 then acts as a safety valve, and is of such strength only as to permit of its being blown out or broken before there is enough pressure to burst the flask or blow off the cover of the mold or otherwise injure the mold.

It will thus be seen that my invention provides, first, for pouring the metal so that no air will be trapped in the mold during the process of pouring; second, for taking off all gases from the mold as rapidly as formed by forming a vacuum in the mold; third, for creating the equivalent of a high "gate" to the mold by atmospheric pressure while pouring; fourth, for so preparing the mold that it will withstand high pressures without distortion, and fifth, for applying a high compression to the metal in the mold while still in a liquid or plastic state.

What I claim is:—

1. In combination, a flask and its base adapted to form the drag, and a flask and its top plate adapted to form the cope, the meeting edges of the flasks being hermeti-

cally sealed, a mold arranged in the flasks and having a feeding passage or channel leading thereto at or near one end and an exhaust passage leading therefrom at or near the opposite end, and means to control the introduction of molten metal to the feeding passage and apply pressure thereto after it enters the mold.

2. In combination, a flask and its base adapted to form the drag, and a flask and its top plate adapted to form the cope, the meeting edges of the flasks being hermetically sealed, a mold arranged in the flasks and having a feeding passage or channel leading to its bottom and an exhaust passage leading therefrom at or near its top, a hopper erected on the plate of the cope and terminating in a cylindrical portion opening into the feeding passage, and a plunger arranged in said hopper and adapted to control the flow of metal from the hopper through the cylindrical portion to the feeding passage and then to be moved toward the feeding passage to apply pressure to the metal fed from the hopper into the feeding passage.

3. In combination, a flask and its base adapted to form the drag, and a flask and its top plate adapted to form the cope, the meeting edges of the flasks being hermetically sealed, a mold arranged in the flasks and having a feeding passage or channel leading thereto at or near one end and an exhaust passage leading therefrom at or near the opposite end, and means to control the introduction of molten metal to the feeding passage and apply pressure thereto after it enters the mold, the exhaust passage being intercepted transversely by a sliding valve.

4. In combination, a flask and its base adapted to form the drag, and a flask and its top plate adapted to form the cope, the meeting edges of the flasks being hermetically sealed, a mold arranged in the flasks and having a feeding passage or channel leading thereto at or near one end and an exhaust passage leading therefrom at or near the opposite end, and means to control the introduction of molten metal to the feeding passage and apply pressure thereto after it enters the mold, the exhaust passage being intercepted transversely by a sliding valve, and a frangible relief valve located in the cope plate.

In testimony whereof I have hereunto set my hand this 2 day of August, A. D. 1917.

SIMON LAKE.
